UNITED STATES PATENT OFFICE

HOWARD PARKER, OF BERLIN, NEW HAMPSHIRE, ASSIGNOR TO BROWN COMPANY, OF
BERLIN, NEW HAMPSHIRE, A CORPORATION OF MAINE

METHOD OF AND APPARATUS FOR COMPRESSING AND TRUING FIBER TUBES

Application filed March 13, 1929. Serial No. 346,597.

This invention relates to a method of and apparatus for compressing and truing the walls of fiber tubes so as to impart to the tubes superior characteristics of density, 5 strength and accuracy of dimensions. An object of the invention is to operate on tubes of fibrous material in such a way as to increase materially their mechanical strength and to ensure uniform accuracy of internal and 10 external diameters throughout the extent of each section of tubing. One type of tubing to which the invention is applicable may be made by winding under pressure on a suitable mandrel a web of wet cellulosic pulp until 15 the desired wall thickness is obtained, removing the mandrel, and carefully drying the tube. The pressure on the web of pulp as it is rolled up on the mandrel tends to cause 20 an interfelting between the fibers of successive convolutions so that no laminated structure can be detected in the resulting tube wall after it has been dried, the fibers being substantially uniformly interfelted in all directions throughout the tube. The making of 25 such tubes is attended with certain difficulties which frequently cause imperfect tubes. This is particularly true of the drying step during which tubes are subject to blistering, warping, and irregular shrinkage unless 30 great care be taken to avoid these difficulties. In spite of the most careful treatment, however, a certain percentage of defective tubes are liable to be produced. In most cases, defective tubes must be partly or wholly 35 discarded. By my invention, fiber tubes are mounted on a mandrel having a diameter equal to the correct interior diameter of the tube, then the tube walls are subjected to high radial pressure, this treatment extending 40 from one end of the tube to the other. As a result, the tube walls are compacted to a uniform thickness, small irregularities being pressed out. The tube is also axially straightened by this treatment, if previously warped 45 out of line, and is made accurately circular in cross section. As a result of this treatment, not only is a superior product produced, but a large part of what would previously have been wasted is salvaged and made into 50 a salable product of excellent quality.

According to the invention, a circular series of fingers are provided which are powerfully pressed inwardly against the outer surface of a tube which is mounted on a mandrel. The inward motion of the fingers is limited to a distance from the axis equal to the correct external diameter of the tube which is being compressed. The fingers engage the tube over an axial length of a few inches, being fed along so that each successive pinch is a short distance further along the tube. Thus the entire tube may be compressed from end to end.

For further advantageous features of construction and operation, reference may be had to the disclosure of the invention in the description thereof which follows, and on the drawings, of which,

Figure 1 is a side elevation of mechanism embodying the invention.

Figure 11 is a fragmentary elevation of the feed screw for the presser head.

Figure 12 is a section on the line 12—12 of Figure 10.

Figure 13 shows in elevation an intermediate support for the feed screw.

95

Figure 14 is a diagrammatic plan of the gearing connecting the driving shaft with the feed screw and the mandrel support.

Figures 1, 2 and 3 illustrate an apparatus for truing and compressing fibrous tubes of

104

considerable length. According to present practice eight feet is a standard length for such tubes but the apparatus illustrated may be made to handle tubes of greater length if desired. As shown, the apparatus comprises an elongated bed 20 upon which is adjustably mounted a headstock 21 and a tailstock 22 to support a mandrel 23 on which is mounted a fiber tube 24 for pressing and truing. The headstock 21 is provided with a live spindle 25 which is rotated by mechanism hereinafter described. The tailstock 22 is provided with a dead spindle 26, the spindles 25 and 26 being movable axially, as by suitable hand wheels 27, 28, to engage and support the ends of the mandrel 23. Slidably mounted on the bed 20 between the headstock and the tailstock is a presser head 29 which is in the general form of a ring which is coaxial with the mandrel 23 when the latter is mounted between the spindles 25, 26. The presser head 29 contains mechanism for successively squeezing or pinching the outer surface of the tube 24, as is hereinafter described, this mechanism operating on a circumferential area of comparatively short length of the tube 24. When treating the entire tube, the presser head with its pressing mechanism is fed from one end of the tube to the other, while the presser mechanism therein rapidly pinches and releases the surface of the tube. In this way, the entire tube is compacted and smoothed. This treatment also removes irregularities not only of diameter but also axial warping so that the finished product is straight and true in all respects. In the embodiment of the invention illustrated in the drawings, I provide connected mechanism for simultaneously feeding the presser head 29 along the bed and rotating the spindle 25, this mechanism being driven by any suitable source of power such as an electric motor 30. The presser mechanism carried by the presser head may conveniently be driven by another motor 31 which, as shown, is mounted on the presser head 29 and travels therewith.

The mechanism for rotating the mandrel and feeding the presser head is illustrated in Figures 9 to 12 and includes a reversing clutch which is manually operable from either end of the bed 20 as by hand levers 32 which are mounted on cross shafts 33. On each of the cross shafts 33 is a lever 34 entering respective recesses in suitable blocks 35, 36, these blocks being both mounted on a common rod 37 so that manipulation of either lever 32 will operate the clutch.

The motor 30, as shown in Figure 3, may be connected as by a belt 38 to a pulley 39. This pulley is mounted on a shaft 40 which carries an elongated pinion 41. The pinion 41 meshes with a loosely mounted clutch gear 42 and also with a second gear 43 which is mounted on a shaft 44. Likewise mounted

on the shaft 44 is a gear 45 which is similar to the gear 43 and which meshes with a loosely mounted clutch gear 46 similar to the gear 42. From the diagram in Figure 14, it may be seen that if the pinion 41 is rotated in a clockwise direction then the gears 42 and 43, which mesh therewith, will rotate in a counterclockwise direction as will also the gear 45. Since the latter meshes with the gear 46, the gear 46 will rotate in a clockwise direction. Hence the clutch gears 42, 46, both of which are loosely mounted, are continually driven in opposite directions and are selectively engageable by a clutch member 47 which is splined on a shaft 48. The clutch member 47 may be moved axially on the shaft 48 as by a fork 49 which is fixed to the rod 37. As shown in Figure 10, a feed screw 50 may be coupled to the shaft 48 to be driven thereby, this feed screw extending substantially the entire length of the apparatus and being engaged by a threaded portion of the presser head 29. Fixed to the shaft 48 is a pinion 51 which meshes with a gear 52, the latter being mounted on a shaft 53. Also mounted on the shaft 53 is a pinion 54 which meshes with a gear 55. The gear 55 is fixed to the live spindle 25 so that whenever the feed screw 50 is rotated to move the presser head, the spindle 25 will be also rotated at a relatively slow speed. As is hereinafter described, the presser elements carried by the presser head 29 are adapted to pinch a portion of the exterior surface of the tube 24, these pinches being in rapid succession and of short duration. It is desirable that the rotation of the tube 24 be capable of momentary interruption during each brief pinch. To this end the clutch gears 42 and 46 may be constructed as indicated in Figure 12. As therein shown, each of these gears may comprise an internal spider consisting of a hub member 56 loosely mounted on the shaft 48, a lining of friction metal 57 being inserted between the hub members and shaft if desired. Extending radially outward from the hub member 56 are a number of lugs 58. Surrounding the spider is a ring gear 59 having inwardly extending lugs 60. As shown in Figure 12, the outwardly extending lugs 58 and the inwardly extending lugs 60 may be uniformly spaced as by blocks 61 of rubber or by other suitable resilient members. As shown in Figure 10, the hub member 56 of each gear is provided with a flange 62 between which and a ring 63 the rubber blocks 61 and the ring gear 59 are held in place. The face of the flange 62 is provided with suitable lugs to interlock with the clutch member 47. Thus when the shaft 48 is being driven through one of the clutch gears 42 or 46, the driving force is taken by the ring gear 59 and transmitted through the rubber blocks 61 to the spider 56 which is interlocked with the clutch member 47.

Thus, when the tube is clamped by the presser mechanism carried by the presser head 29, it can stop rotating momentarily due to the compressibility of the rubber blocks 61. 5 When the tube 24 is released by the presser mechanism, the blocks 61 are permitted to expand to their regular shape and in doing so jump the clutch member 47 ahead to make up for the stoppage. 10 The presser head 29 comprises a casing 162 which may have a ring-shaped recess to receive a ring gear 163. The presser mechanism includes a circular series of presser fingers 64 arranged concentrically within the gear 163, each finger being of general key- 15 stone shape, as shown in Figure 4, and comprising an outer member 65 which supports an inner member 66 in such a manner as to permit a slight relative motion in a direction parallel to the axis of the apparatus. To the inner face of each member 66 is secured a removable element 67, each element having a contacting face 68 arranged to engage against the surface of a tube 24. The elements 67 are so shaped that, when they are moved to their inmost position toward the axis of the mandrel, their faces 68 form a substantially continuous cylindrical surface having a diameter equal to that desired for 20 the exterior of the tube 24. The element 67 may be releasably attached to the elements 66 as by screws 69 which permit easy removal of the elements 67 so that they may be quickly replaced by different elements in case it is 25 desired to operate tubes of larger or smaller diameter. The presser elements 67 which with the elements 66 and 65 constitute the fingers 64, are each moved radially inward and outward as a unit. This may be accomplished by a series of rollers 70 which may ride within a ring 71 mounted within the ring gear 163. The rollers 70 also ride on the outer ends of the fingers 64, these ends being sloped, as shown in Figure 4, to a high portion in the center so that as the rollers 70 ride on the outer end faces of the fingers 64, the latter are necessarily forced radially inward. The inmost position of the presser faces 68 is thus determined by the maximum 30 radial length of the fingers 64 plus the diameter of the rollers 70. There are preferably as many rollers 70 as there are fingers 64, so that as the rollers move from the low points on the outer end faces of the fingers, as shown 35 in Figure 4, to the high points of these faces, the fingers are simultaneously forced inwardly to their inmost positions and are thereupon simultaneously retracted to the positions as shown in Figure 4. The retracting means may comprise a pair of simple leaf springs 72 supported by a fulcrum member 73, the outer ends of the leaf springs 72 being clamped as by angle pieces 74. In order to keep the rollers 70 in proper spaced relation, 40 each may be mounted on a shaft 75, the ends of which are journaled in a pair of rings 76. Ball bearings 77 may also be provided to take any axial thrust which may be impressed on the rollers 70 relative to the casing 162. The elements 66 and 67 of the fingers 64 are permitted a limited amount of relative movement in a direction parallel to the axis of the mandrel, so that in case the feed of the presser head 29 is continued during a pinching engagement of the fingers with a tube a certain amount of axial leeway is afforded. Since the fingers 64 under such circumstances are usually under heavy radial pressure from the rollers 70, this yielding movement is facilitated by ball bearings 78 between the elements 65 and 66. In order to keep the fingers properly aligned, I may provide a pair of rings 79, 80, these rings being secured as by bolts 81 to angle rings 82 which in turn are bolted to the casing 162. The confronting end edges of the rings 79, 80 may be slotted as at 83, to receive portions of the elements 65, whereby the fingers 64 are prevented from traveling around the axis with the rollers 70. The confronting faces of the rings 79, 80, may also be provided with recesses 84 to receive plungers 85 on which are mounted compression springs 86, the latter being provided for the purpose of normally maintaining the fingers 64 in their proper axial relation to the rings 79, 80. The ring gear 163 may be driven by a pinion 87, this pinion 87 being connected to the motor 31 as by a train of suitable gearing mounted in a housing 88. As the ring gear 163 is rotated by the pinion 87, the engagement of the ring 71 with the rollers 70 causes the latter to roll on the outer faces of the fingers 64. Thus the fingers are moved rapidly in and out by the rollers 70 and the leaf springs 72, rotation of the fingers around the axis being prevented by their engagement in the recesses 83 of the fixed rings 79 and 80. 45 The feed screw 50 may be of such length as to sag somewhat under its own weight if supported at its ends only, in which case it should be supported at one or more points between its ends. When the presser head 29 is in the middle of its travel on the bed 20, it supports the feed screw 50 at that point. When, however, the presser head moves to either end of its travel, auxiliary supporting means for the feed screw 50 should be provided. To this end, a suitable trough 89 may be provided to fit against the lower side of the feed screw 50 near the mid point thereof, as shown in Figure 13. This trough may be supported by a pair of parallel arms 90, 91, which are pivotally connected thereto. The arms 90, 91 are also pivotally mounted on a suitable bracket 92, one or both of these arms being provided with a weight 93 at the lower end thereof. This structure provides an adjustable support for the screw 50 which may be temporarily moved aside by the presser head as it travels past. As soon as the presser 50

head has passed in either direction, the weight 93 restores the trough 89 to its supporting position.

It is also desirable to support the mandrel 23 near its mid point to prevent sagging thereof under its own weight. To this end I may employ a pair of supports 94, one of these being on each side of the presser head 29. As shown in Figures 7 and 8, each support 94 may be carried by a sliding base 95 on which they are yieldingly mounted so as to be capable of limited depression against the action of a spring 96. The support 94 may be replaced by other supports of different heights to accommodate tubes of different diameters. The bases 95 slide on the bed 20. As the presser head 29 moves along the bed it comes up against the slide 95 ahead of it and pushes it to the end of its travel, leaving the slide behind it in the middle portion of the bed 20. When the travel of the presser head is reversed, it drags along behind it the slide it has just pushed until it reaches the middle portion of the bed 20, whereupon it drops this slide and pushes the other slide ahead of it to the limit of its travel in that direction, this action being successively repeated with each trip of the presser head from one end of the bed to the other. In order to drag back the slides 95 to the middle portion of the bed, the presser head 29 may be provided with a finger 97 projecting outwardly from each face thereof. Each finger is provided with a beveled end 98 and a notch 99 to cooperate with a plunger 100 carried by the slide 95 and pressed downwardly by a suitable spring 101. As the presser head travels along the bed 20 upon reaching the slide in front of it, the plunger 100 rides up on the beveled face 98 and trips into the notch 99, the support with its slide 95 being thereafter pushed ahead until the presser head reaches the end of its travel. When the presser head is started on its travel in the reverse direction, the engagement of the plunger 100 in the slot 99 causes the slide 95 to be pulled after the head 29. The lower edge of the plunger 100 rides on a rail 102 which extends parallel to the feed screw 50 and is provided with a raised portion 103 at the middle of the bed 20. When the plunger 99 reaches the raised portion 103 of the bar 102 it rides upwardly on the sloping face, releasing the lower end from the notch 99 and permitting the presser head to continue its travel without pulling the support along any further. Thus the support is left in the approximate middle of the bed 20 to hold the mandrel 23 and the tube 24 and to prevent sagging of the same. Meanwhile the presser head has come up against the other slide 95. This is pushed to the end of the travel of the presser head and is thereafter brought back to the middle of the bed as hereinbefore described. In order to prevent over-travel of the presser head in either di-

rection, I may provide a pair of stops 104 mounted on the rod 37. These stops are located in the path of a portion of the presser head so as to be engaged thereby when the presser head reaches the end of its travel. The push of the presser head against either of the stops 104 moves the rod 37 longitudinally and thus disengages the clutch, stopping the rotation of the feed screw 50. The clutch may then be thrown in reverse connection to start the travel of the presser head in the opposite direction.

The mandrel 23 which supports the tube to be pressed must be of sufficient strength to withstand the heavy pressures which may be exerted thereon by the fingers 64 through the wall of the tube. It is also desirable, and in many cases necessary, that the mandrel be collapsible to permit its ready removal from a tube which has been treated, also to permit its insertion into a tube having an interior diameter just equal to or slightly less than standard. For this purpose the mandrel 23 may comprise a central wedge-shaped member adapted to slide between two members which are tapered in the opposite direction so that the three members, when their ends are flush, have together a circular cross-section at any point along the mandrel, as indicated in Figures 4 and 7. The central member may be slidably dovetailed to the other two members as shown.

I claim:

1. The method of truing the walls of a tube which comprises rigidly supporting the interior surface thereof and successively pressing on short overlapping circumferential areas of the outer surface of the tube while the inner surface is so supported.

2. The method of treating a tube, which comprises rigidly supporting the interior surface thereof, applying radial pressure on the outer surface of the tube by a series of brief pinches over a relatively short length of tube surface, the pressed area advancing progressively between pinches from one end of the tube to the other.

3. The method of truing the diameters of fiber tubes, which comprises rigidly supporting the inner surface of a substantially dry fiber tube at the desired internal diameter, and pressing successive overlapping circumferential areas of the outer surface inwardly to the desired external diameter.

4. Apparatus for treating a fiber tube, comprising a mandrel having a diameter equal to the desired inner diameter for the tube, means for successively pressing short circumferential areas of the outer surface of the tube to desired outer diameter, and means for relatively moving the work and said pressing means axially thereof between successive pressings a distance less than the axial length of a pressed area.

5. Apparatus for treating a fiber tube, com-

prising a mandrel, means for supporting said mandrel at its ends, a presser head, a circular series of presser fingers carried by said head about said mandrel, means carried by said head for simultaneously moving said fingers inwardly and outwardly, said fingers having faces forming together a substantially cylindrical surface when the fingers are in their inmost position, and means for relatively moving said mandrel and head in the direction of their axes.

6. Apparatus for truing a fiber tube, comprising an elongated bed, a headstock and tailstock adjustably supported adjacent the ends of said bed, a mandrel demountably carried between said headstock and tailstock over said bed, means for rotating said mandrel, a feed screw supported by said bed parallel to said mandrel, a presser head slidable on said bed and operatively connected to said feed screw, means for rotating said feed screw selectively in either direction, means for automatically stopping the rotation of said screw when the presser head reaches its limit of travel on said bed in either direction, a circular series of fingers carried by said presser head and movable radially inward to a predetermined distance from the axis of said mandrel, and means carried by said head for reciprocating said fingers to and from their inmost position.

7. Apparatus for treating a fiber tube, comprising a mandrel capable of being inserted in a tube, means for supporting said mandrel at its ends, a presser head around said mandrel, means for moving said presser head along said mandrel in an axial direction, and means carried by said head for pressing a short circumferential area of a tube on said mandrel to a predetermined diameter.

8. Apparatus for truing a fiber tube, comprising a mandrel to be inserted within said tube, means for rotatably supporting said mandrel by its ends, means for rotating said mandrel while thus supported, a presser head around said mandrel and slidably longitudinally thereof, means for feeding said presser head along said mandrel, and means carried by said presser head for shaping a tube on said mandrel, said shaping means including a circular series of fingers mounted for limited radial movement, means for resiliently pressing said fingers radially outward, and means for positively moving said fingers inwardly to a limiting position in which the inmost faces of said fingers are all at a predetermined distance from the axis of said mandrel.

9. Apparatus for truing a fiber tube, which comprises means for rigidly supporting the inner surface of a fiber tube, means for pressing inwardly on short circumferential areas of the outer surface of the tube, said pressing means including a circular series of presser fingers movable radially inward to a pre-

terminated distance from the axis of said tube, and a presser head carrying said fingers, means having a resilient connecting member for rotating said tube on its axis, means for feeding and pressing said head along said tube, and means yieldingly supporting said fingers in said head for limited motion relative thereto longitudinally of the tube, whereby said fingers may grip a rotating tube for brief periods without interruption of the rotation of the tube or of the feed of the presser head.

In testimony whereof I have affixed my signature.
